Application May 13, 1942, Serial No. 442,842

8 Claims. (Cl. 200—21)

This invention relates to improvements in ignition apparatus for internal combustion engines and, more particularly, to the distributor mechanism thereof.

The invention is especially adapted for use in connection with the ignition apparatus of airplane engines and is herein disclosed by way of illustrative example, in connection with a 16 cylinder, V-type airplane engine, firing at irregular angular intervals of rotation of its crank-shaft.

The invention has for an object the provision of a distributor having a stationary feed ring connected to the high tension terminal of the ignition apparatus and provided with a plurality of contacts angularly spaced in a circular series and a cap having a plurality of contacts angularly spaced in a circular series and adapted for connection one to each of the spark plug wires, together with a rotor having means thereon for connecting terminals of the first series one at a time to terminals of the second series.

The invention also has for an object the provision of a distributor of the class described wherein individual electrodes, one at each end of the rotor, are provided, and are adapted to function alternately in the work of connecting contacts of the first series to contacts of the second series.

The invention has for another object the provision of a distributor of the class described wherein the connections to the various spark plug wires are made at irregular angular intervals of rotation proportioned to the irregular angular intervals of rotation of the engine crank-shaft at which the engine fires.

The invention has for another object the provision of a distributor arranged within a casing which may be sealed up, when required, and which has means for connection to a supercharger when required.

The invention has for another object the provision on the rotor of fan blades located adjacent the electrodes for the purpose of circulating the air in the distributor and particularly of removing ionized air from the zone in which the contacts and electrodes are located.

Another object of the invention is to provide in connection with the fan blades described, co-operating stationary vanes on one of the contact-bearing rings, such vanes enhancing the action of the fan blades on the rotor and also serving, by their location between successive contacts as barriers.

A further object of the invention is to pro-

vide a distributor in which all of the spark plug wires are led out through a radio-shielding tube located at its point of connection to the distributor coaxially of the latter.

5 A further object of the invention is to provide in a distributor of the general class described a weatherproofed ventilation and drain passage connected to the distributor chamber.

A further object of the invention is to provide a combined drain and ventilation passage for the distributor chamber and a valve for controlling such passage, characterized in that the valve automatically closes whenever the distributor is being supercharged.

10 15 These and other objects will best be understood as the detailed description proceeds and they will be pointed out in the appended claims.

The invention will be disclosed with reference to the accompanying drawings, in which:

20 Fig. 1 is a sectional elevational view of an ignition apparatus embodying the invention—this view being taken on the line 1—1 of Fig. 2;

Fig. 2 is a top plan view with the cover and the rotor of the distributor removed;

25 Fig. 3 is a sectional plan view taken on the line 3—3 of Fig. 1;

Fig. 4 is a fragmentary sectional elevational view taken on the line 4—4 of Fig. 2;

Fig. 5 is a fragmentary sectional elevational view taken on the line 5—5 of Fig. 3;

Fig. 6 is a fragmentary cross sectional view of the distributor cap;

Fig. 7 is an end elevational view of the distributor rotor;

Fig. 8 is a fragmentary sectional elevational view taken on the line 8—8 of Fig. 3;

Fig. 9 and 10 are fragmentary sectional views both taken on the line 9—9 of Fig. 2;

Fig. 11 and 12 are cross sectional views taken on the lines 11—11 and 12—12 respectively of Fig. 10;

Fig. 13 is a fragmentary cross sectional view taken on the line 13—13 of Fig. 3;

Fig. 14 is a bottom plan view of a packing element in the distributor cap; and

Fig. 15 is a fragmentary sectional elevational view of a ventilation and drain valve for the distributor.

Referring to Fig. 1, these drawings, the distributor and the associated breaker point mechanism, are contained within a metallic casing C which entirely encloses them and completely shields them so far as radio interference is concerned. This casing has a peripheral wall 20, an end wall 21 suitably fixed as by screws 22, to one

end of wall 20 and a cover 23 suitably fixed as by screws 24 (Fig. 3) to the other end of wall 20. This casing provides within it a distributor chamber D, the same being formed between the cover 23 and a cross wall 25 inside the casing, which wall forms one end wall of chamber D. This wall has openings 25' therethrough. The rotor shaft is shown at 26 and it is mounted in suitable bearings in walls 21 and 25. The cover 23 has a tubular portion 23' providing a central opening coaxial with shaft 26. This opening is closed by the elbow 27, which forms part of a conduit for the spark plug wires w. The elbow is suitably fixed to cover 23, as by screws 28.

The space in casing C between the walls 21 and 25 may, if desired, and as shown, house the spark generating means. As illustrated, such means includes primary and secondary coils 29 and 30 respectively, which in this case form part of a magneto and are energized intermittently at proper intervals thereby. The coils are housed in a plastic case 31 and secured, as by screws 32, to partition 25. The wire 33, shown in Fig. 2, as connected to partition 25 and thereby grounded, is connected to one terminal of both coils. The wire 34 in Fig. 2 forms the other terminal of the primary coil. The other terminal of the secondary coil includes a wire 35 (Fig. 1), and a metal button 36 connected thereto. These are located in the lower portion of a substantially L-shaped insulating tube 37 which at its lower end is cast in the plastic case 31 and the upper end of which rises vertically into the lower part of chamber D. The other magneto elements (not shown) may be contained within casing C, below the coil case 31.

The distributor comprises two contact-bearing rings of insulating material and an intervening brush-carrying rotor. The inner ring 38 is an annulus and has a plurality of legs 39, one of which is shown in Fig. 9, which engage wall 25 and are secured thereto, as by screws 40. Embedded in ring 38 is a metallic feed ring 41 (Fig. 2) from which extend a plurality (8 in this case) of contacts 42 which are arranged at equally-spaced angular intervals (45° in this case) in a circular series. One of these contacts 42 is shown in detail in Fig. 5. Fig. 2 shows that these contacts extend in a direction parallel to the axis of the ring 38 and are encompassed by a marginal circular flange 43 on such ring. At one point (Figs. 1 and 2), the feed ring 41 is enlarged to receive a stud 44 (Fig. 1) bearing a spring 45 which makes connection with the high tension terminal of coil 30. As shown, this connection is made through the intermediary of a resistor 46, located in insulator 37 and contacting with the button 36 and spring 45. This resistor may be used whenever it is found necessary. Its purpose is to smooth out oscillations in the high tension circuit. The ring 38 has cast therein a tubular insulator 47 which telescopes the insulator 37 to increase the leakage path between the high tension circuit in the neighborhood of the part 45 and the metallic and grounded casing 20 sufficiently to prevent flash over.

The outer distributor ring is generally in the form of a shallow cup or cap having a base 48 and a circular marginal flange 49 which telescopes and closely fits the flange 43 of the inner ring 38. The two rings have complementary finished shoulders which abut with a close fit as shown. The closely interfitting rings prevent flashing from the contacts to the metallic casing 20. This outer ring is connected to cover 23 by two or more screws 50, each threaded into a metal

insert 51 in the base 48. This base has an axially-directed and outwardly extending hub portion 52 which passes through the central opening in the cover. This hub portion is provided with a plurality of sockets 53 for the spark plug wires w. In this case, there are sixteen such sockets and they are arranged in two coaxial circular series. The base 48 of the outer distributor ring carries a circular series of contacts 54 (16 as shown in Fig. 3). These contacts (Figs. 8 and 13) project inwardly from the base 48 of the outer ring in a direction parallel to the axis of such ring. As shown, these contacts are integral with wires 55 which are embedded in the base 48 and connect the contacts, one to each of the terminals in the base of the sockets 53. These sockets are arranged in two coaxial circular series of eight so that eight of the wires 55 are of the length shown in Fig. 8 to reach the sockets of the inner series and eight of them are of the length shown in Fig. 13 to reach the sockets of the outer series. In Fig. 3, each contact has beside it a numeral indicating the number of the cylinder to which it is to be connected. The relative locations of the two series of contacts are shown in Fig. 3—each contact 42 lying centrally between the two adjacent contacts 54 except the two lowermost ones shown in Fig. 3, is an integral and radially extending barrier 56 (see also Fig. 6). These barriers also cooperate like the fixed blades of a turbine with movable blades carried by the distributor rotor.

This rotor (Figs. 3 and 8) comprises a diametrically extending member 57 of insulating material, fixed centrally by cap screws 58 to a flanged hub 59, which is splined to the shaft 26. A nut 60 (Fig. 1) clamps flange 59 against the inner race 61 of the ball bearing 62 and the race 61 against a flange 63 on the shaft. The rotor has brushes (Fig. 8) one on each end thereof to cooperate with both the contacts 42 and 54. One brush (see also Fig. 7) has a terminal 64 to cooperate with the contacts 54 of the outer series and a terminal 65 to cooperate with the contacts of the inner series. These terminals are electrically interconnected by an integral bent portion 66 which is embedded in the plastic material of which arm 57 is made. The other brush has similar terminals 64' and 65' and a similar connector 66' interconnecting them in a similar manner. These terminals 64 and 65 and the terminals 64' and 65' are located at angularly spaced intervals—being separated by an angle equal to that between any contact 42 and either of the two adjacent contacts 54, as will be clear from Fig. 3. These terminals 64 and 65 as well as the terminals 64' and 65' are also located in different transverse planes. The outer faces of each brush terminal which moves in close relation to the contacts is finished as are also the contacts. The trailing face of each such terminal is exposed (Figs. 3 and 7) as this takes any burning which may occur from the spark when the latter is drawn out as the brush and contact separate. There is a lateral barrier 67 between the inner and outer terminals of each brush.

The rotor arm carries near both its outer ends and projecting from both faces thereof fan blades 68 which are mounted generally radially of the rotor and spaced by a small angle behind the trailing face of each brush terminal. The outer blades move in close proximity to the barrier blades 56 and cooperate therewith somewhat as in a turbine. The purpose of the blades is to

stir up the air within the distributor chamber D and particularly to drive out from the peripheral region thereof the air which has been ionized by high tension discharges of electricity therethrough and to replace such air by air drawn from the inner portion of the chamber. Ionized air increases the liability to leakage because it is more easily penetrated by the sparks than is un-ionized air.

Referring now to Figs. 8 and 13, each spark plug wire *w* has fixed on and electrically connected to the inner end of its metallic portion a metallic washer *69*. Each wire *w* has an axially-directed screw-threaded end *70* which enters the base of a socket *53*. A spring *71* is screwed onto each said end *70* and held in place thereby. When each wire *w* is thrust into its socket *53*, the washer *69* engages and slightly compresses the spring *71*, thereby making and maintaining good electrical contact between each wire *w* and its wire *55*.

The spark plug wires *w* pass through holes in a rubber disc *72*, having integral tubular extensions *73* one for and inserted into each socket *53*. The hole in each extension closely fits the outer and insulated portion of its wire *w*. This member *72* is separately shown in Fig. 14. The washers *69* are large enough in diameter to engage the inner ends of these extensions *73* (Fig. 13) and prevent the wires from being pulled out of the rubber member. This member also has a rim portion *74* which fits into the space between the hub *52* and the sleeve *23*. The disc *72* also has a central projection *75* of irregular cross section to fit in a hole *75'* of the same cross sectional shape in hub *52*, whereby the disc may be so located so that the proper wires *w* enter the proper sockets *53*. A disc *76*, also perforated to receive the wires *w*, serves as a gland plate, being engaged by a shoulder in elbow *27* and serving, when the elbow is bolted in place, to compress the rubber disc *72*. The rubber disc, which is compressed between plate *76* and the outer end face of hub *52* is caused to bulge against each wire *w* and against the inner wall of elbow *27*, thereby sealing off the elbow from the distributor chamber.

Suitable breaker mechanism is provided as best shown in Fig. 2. As shown, there are two breaker arms which are operated in proper timed relation from an eight-lobed cam *77*, formed on the inner end of hub *59* and thereby fixed to shaft *26*. One breaker arm *78* is pivoted on a stud *79* fixed to a plate *80*. This plate is turnably mounted on the hub *81* which supports the upper bearing for shaft *26*. Screws *82*, passing through slots in plate *80*, are threaded into wall *25* and serve to fix the plate in its various positions of adjustment. The other breaker arm *83* is pivoted on a stud *84* fixed to a smaller plate *85*. The latter is turnable about hub *81* and angularly adjustable relative to plate *80*. Screws *86* passing through slots in plate *85* are threaded into plate *80* and serve to clamp plate *85* to plate *80* and hold the two together in their various positions of relative adjustment. An eccentric *87* located in a notch in plate *85* is pivoted in plate *80* and serves as a means for moving plate *85* on plate *80* when screws *86* are loosened. Arm *78* carries at one end a breaker point *88* and at the other end a cam follower *89* of relatively small angular extent. Arm *83* carries at one end a breaker point *90* and at the other end a cam follower *91* of relatively large angular extent. The fixed breaker point *92* with which point *88* cooperates is fixed to

a plate *93* turnable about stud *79*, when the clamping screws *94* are loosened by turning the eccentric *95*, in a manner similar to that described in connection with plate *85*.

The point *88* is connected by a spring *95'* to an insulated terminal *96* and the spring acts to press the follower *89* against cam *77*. The fixed breaker point *97* with which point *90* cooperates is similarly mounted on a plate *98* adjustable by an eccentric *99* about the axis of stud *84* and held to plate *85* in various positions of adjustment by clamping screws *100*, in a manner similar to that described in connection with plate *85*. A spring *101* connects the point *90* to an insulated terminal *102* on plate *98*. Thus, both breakers may be moved together about the axis of shaft *26* or either one may be moved independently of the other about said axis. The degree of breaker point opening is controlled by adjusting the plates *93* or *98* on plates *80* and *85* respectively.

The two breakers are electrically connected in parallel. The described terminal wire *34* of the primary coil is connected to insulated terminal *102* and thus to movable breaker point *90*. A wire *103* connects terminal *102* to the insulated terminal *104* of a condenser within a metallic case *105* to which the other terminal of the condenser is connected and which is fixed by screws *106* to plate *80* and thereby grounded. A wire *107* connects the wire *103* and insulated terminal *104* of the condenser to the insulated terminal *96* and thus to movable breaker point *88*.

The breaker arm *78* with the narrow shoe *89* is arranged to be so actuated by cam *77* that its breaker points *88*, *92*, remain open for 30° and closed for 15° of each 45° cycle of movement of the cam. The breaker arm *83* with the wide shoe *91* is arranged to be so actuated by cam *77* that its breaker points *90*, *97* remain open for 38° and closed for 7° of each 45° cycle of operation. The breaker arms are so spaced that when breaker arm *78* is midway in its angular dwell in closed position the breaker arm *83* is midway in its angular dwell in open position. Assuming that cam *77* is turning clockwise as viewed in Fig. 2, when it has turned $7\frac{1}{2}^\circ$ from the illustrated position, the arm *78* will be moved to open the breaker points *88* and *92*. The wide shoe of arm *83* will still be engaged by a high point of the cam and accordingly, the breaker points *90* and *97* are open. Thus, the opening of breaker points *88* and *92* will cause an opening of the primary circuit and the production of a spark. When cam *77* has moved $15\frac{1}{2}^\circ$ from the illustrated position, the breaker points *90* and *97* will engage. At the same time, the breaker points *88* and *92* remain open. When cam *77* has moved $22\frac{1}{2}^\circ$ from the illustrated position, the breaker arm *83* will have been moved to open its breaker points *90* and *97* at a time when the breaker points *88* and *92* are still open. Thus, the opening of points *90* and *97* will cause an opening of the primary circuit and the production of a spark. This second spark occurs 15° after the first spark. When cam *77* turns still further into a position $37\frac{1}{2}^\circ$ from that illustrated, the breaker points *88* and *92* will close but the breaker points *90* and *97* remain open. When cam *77* turns still further and assumes a position $52\frac{1}{2}^\circ$ from that illustrated, the breaker points *88* and *92* will be opened at a time when the breaker points *90* and *97* are still open, thus again opening the primary circuit and producing another spark at angular interval of 30° after the second spark. This completes one cycle of operation of the breaker points. It will thus

be seen that the breakers cause the primary circuit to be opened alternately at different intervals—first at 15° and then at 30°. The magneto, if one is used, will of course be timed to produce effective changes of flux at similar intervals, timed to correspond with the opening of the primary circuit by the breaker mechanism as above described.

A connection has been provided for the usual ground switch, which when closed short circuits the primary coil and prevents the generation of sparks. Referring to Fig. 4, a conducting strip 108 is fixed at one end to plate 80 by one of the cap screws 82, which serve to clamp plate 80 to wall 25, and is insulated from plate 80, wall 25 and screw 82 as indicated. A wire 109 (Fig. 2) connects said end of strip 108 to the insulated terminal 96 above described. The other end of strip 108 underlies the ring 38 of insulation as clearly shown in Fig. 4. A wire 110, adapted for connection at one end to the ground switch, has its other end electrically connected to a metallic cap 111 secured on the inner end of an insulator 112, through which the wire extends. The insulator is removably mounted in a nipple 113 secured in casing 20 and has a flanged outer end to seat in a counterbore in said end. The insulator 112 is held in place by a cap 114, which compresses packing 115 against said flanged end to seat it in the counterbore and also to seal the joint between the wire and insulator. When the insulator 112 is mounted in place as shown, the cap 114 engages one end of a spring 116 and slightly compresses the same. This spring at its other end, is screwed in a threaded stud 117 fixed to the under face of strip 108 and depending therefrom.

The distributor chamber is provided with an opening 118 (Fig. 2) to receive a pipe, such as 119, which connects with a supercharger, whereby the pressure within the chamber may be maintained at the desired predetermined value. When the supercharger is used, it will be understood that all other outlets from the chamber are closed.

A drain for the distributor chamber is also provided, whereby condensation may be removed by gravity flow or blown out if desired. The longitudinal center line of the casing 20—23, defined by the longitudinal axis of shaft 26, is normally inclined about 15 degrees to the horizontal so that the outer end (right hand end as viewed in Figs. 1 and 8) is lower than the inner end. At the lower outer end of the distributor chamber, a threaded opening 120 (Figs. 10 and 15) is provided. A hole 121 in ring 48 provides communication between the interior of distributor chamber D and hole 120. This hole may be closed with a plug when a supercharger is used—the operator removing the plug and draining the chamber before the start of a flight and then replacing the plug.

Another expedient is shown in Fig. 15. A fitting 122 is screwed into hole 120. This fitting has a through passage 123 with a counterbored outlet end and, in the counterbored part is slidably mounted a valve 124, yieldingly held to its seat by a spring 125. A cap 126, acting as a seat for spring 125, also carries a frusto-conical member 127 to cooperate with valve 124 and has outlets 128. Normally, the spring raises the valve out of engagement with member 127, leaving the outlet open for drainage of water or for entrance of air for ventilation purposes. However, when the supercharger is used, the pressure of the air

on valve 124 moves the same toward and holds it against the member 127, thereby automatically closing the outlet when such closure is necessary.

A weatherproofed ventilation opening is shown in Fig. 10. A tube 129, having an axial passage 130 and a flange 131 is screwed into hole 120 until the flange abuts the hub on casing 23. A cap, having an end wall 132 and a peripheral wall 133, is mounted on the tube as shown—being secured thereto by a cap screw 134. The cap forms with the tube and its flange, an annular chamber 135 which is in constant communication with passage 130 by means of a hole 136 extending diametrically through tube 129. The screw 134 closes the outer end of passage 130. Two series of holes are formed in the cap, one on each side of passage 136 and spaced therefrom by a distance at least as great as the diameter of hole 136. The holes of one series are marked 137. They are formed in the peripheral wall 133 of the cap. The holes of the other series are marked 138. They are formed in the end wall 132 of the cap as shown in Fig. 12. The axes of the holes 137 and 138 are located in radial planes which are different than the radial plane in which the axis of hole 136 is located. The radial distance between the outer periphery of tube 129 and the inner periphery of wall 133 is at least as great as, and preferably somewhat greater than, the diameter of holes 137 or 138. The arrangement is such that rain, which may drive in through any of the openings 137 or 138, cannot readily enter the hole 136 and reach the passage 130 which connects with the distributor chamber. This is true irrespective of what position the casing 23 and the cap 132—133 may assume. This cap may be vertically pointed, either up or down, approximately horizontal as shown, or at any angle in between these extremes. The purpose of the arrangement is to allow ventilation of the distributor without allowing entrance of water. It may be used with or without the valve device of Fig. 15.

In operation, the shaft 26 is driven at one half crankshaft speed. Sparks are produced sixteen times during each revolution of shaft 26, the angular intervals between successive sparks being alternately 15 degrees and 30 degrees, corresponding respectively to 30 and 60 degree intervals of rotation of the engine crankshaft. The breaker mechanism, as above described, serves to open the circuit of the primary coil 29 at the intervals described. The distributor rotor, moving with the breaker cam 77, successively connects the feed ring to the spark plug wires in the proper order and alternately at intervals of 15 and 30 degrees. For example, the rotor arm 57 turning clockwise as viewed in Fig. 3, will after $7\frac{1}{2}$ ° of movement connect the contact 54 for cylinder No. 8 with the feed ring. This is done by the brush 64, 65, 66 at one end of the rotor—the terminal 64 moving opposite said contact 54 and the terminal 65 moving opposite a contact 42 of the feed ring. This position of the rotor corresponds to the above described position of the cam 77 when the breakers are actuated to open the primary circuit after $7\frac{1}{2}$ ° movement of the cam from the illustrated position. As the rotor continues to turn in a clockwise direction, the brush 64', 65', 66' at the opposite end of the rotor will connect the contact 54 for No. 7 cylinder to a feed ring contact 42. This occurs after the rotor has moved 15 degrees from the last-described spark-producing position and at the same time that the breakers open the pri-

mary circuit. Continued movement of the rotor over a 30 degree interval will bring the brush 64, 65, 66 into position to connect the contact 54 for No. 6 cylinder to the feed ring. This occurs simultaneously with another opening of the primary circuit by the breaker mechanism. The rotor, in continued movement, successively connects the contacts 54 to the feed ring in the following order: 5, 4, 3, 2, 1, 16, 15, 14, 13, 12, 11, 10 and 9—thus completing the cycle. The connection is made first by one brush and then by the other and alternately at 15 and 30 degree intervals.

The distributor is completely shielded to prevent interference with radio. The shielding is accomplished by a metallic casing which completely surrounds and encloses the distributor and the breaker mechanism. This casing, comprising the members 20, 21 and 23 effects the result in an effective manner because the number of joints in the casing are reduced as low as possible. Joints in the casing increase the resistance and thus reduce the effectiveness of the shielding. The elbow 27 which is part of a conduit forming part of the so-called "harness" used on airplane engines, also extends the shielding to the spark plug wires as is desired. The connection of this elbow to the distributor cap coaxially of the same is important. It allows one to use simply two different lengths of contact wires, such as 55, as against many prior art constructions in which each wire is of a different length.

The distributor construction is important because of its simplicity of construction which adapts it for quantity production at low unit cost. Two moldings of suitable insulating material are provided, one having embedded therein the feed ring and contacts and the other the spark plug contact-bearing wires 55, together with an intervening rotor, bearing brushes only at its ends. These elements are readily and inexpensively manufactured and readily and easily assembled into the casing which encompasses them. No electrical connections to the moving rotor are required. All contacts are outside the rotor. The contacts of both series are equidistant from the axis of the rotor and the brushes on the rotor leave the contacts of both series at the same angular velocity, providing a double break in the high tension circuit to each cylinder. The arrangement is especially suitable for engines having a large number of cylinders because the contacts can be arranged in a circular series of large diameter and this enables ample spacing between successive contacts. Also, the arrangement of brushes on the rotor enables the solution of the problem of distribution at uneven angular intervals.

Thus the invention provides an improved distributor especially adapted for use in connection with airplane engines and accomplishing the objects hereinabove set forth.

What we claim is:

1. A distributor, comprising, a casing, a shaft 65 mounted therein, a first circular series of contacts mounted in said casing in coaxial relation with said shaft and located between two parallel planes transverse to the axis of said shaft, a second circular series of contacts also mounted in said casing in coaxial relation with said shaft and located between two other parallel planes transverse to said shaft and spaced axially from the first-named planes, an electrical connection between all the contacts of the first series and 75

adapted for connection to a source of supply of electricity, connections for spark plug wires leading one from each contact of the second series, a rotor arm fixed to said shaft, an electrical connector fixed to and insulated from one end of said arm and adapted intermittently to connect contacts of the first series one at a time to contacts of the second series.

2. A distributor, comprising, a casing, a shaft 10 mounted therein, a first circular series of contacts mounted in said casing in coaxial relation with said shaft and located between two parallel planes transverse to the axis of said shaft, a second circular series of contacts also mounted in said 15 casing in coaxial relation with said shaft and located between two other parallel planes transverse to said shaft and spaced axially from the first-named planes, an electrical connection between all the contacts of the first series and 20 adapted for connection to a source of supply of electricity, connections for spark plug wires leading one from each contact of the second series, a rotor arm fixed to said shaft, an electrical connector fixed to and insulated from one end of said 25 arm and terminating with contacts which are spaced axially as well as angularly with respect to said shaft and which are adapted intermittently to connect contacts of the first series one at a time to contacts of the second series.
3. A distributor, comprising, a casing, a shaft mounted therein, a first circular series of contacts 30 mounted in said casing in coaxial relation with said shaft and located between two parallel planes transverse to the axis of said shaft, a second circular series of contacts also mounted in said 35 casing in coaxial relation with said shaft and located between two other parallel planes transverse to said shaft and spaced axially from the first-named planes, an electrical connection between all the contacts of the first series and 40 adapted for connection to a supply source of electricity, connections for spark plug wires leading one from each contact of the second series, a rotor arm fixed centrally to said shaft and extending diametrically of said casing and series of contacts and carrying one on each end thereof a connector insulated therefrom, said connectors operating alternately to connect contacts of the 45 first series one at a time to contacts of the second series.

4. A distributor, comprising, a casing, a shaft mounted therein, a first circular series of contacts 50 mounted in said casing and equally spaced around the axis of said shaft and in coaxial relation therewith, a second circular series of contacts mounted in said casing and equally spaced around the axis of said shaft in coaxial relation therewith, the second series having twice as many contacts as the first series, each of the contacts of the first series lying between and equally spaced angularly from two contacts of the other series, the contacts of each series located between two parallel boundary planes transverse to said axis and the boundary planes of one series being separated in a direction axially of said shaft from the boundary planes of the other series, a rotor arm fixed centrally to said shaft and extending diametrically of said casing, electrical connectors one at each end of said arm fixed to and insulated therefrom, each connector having two terminal ends which are axially spaced to cooperate one with contacts of the first series and the other with contacts of the second series, each connector having its terminal ends angularly spaced by the same amount as the

angular spacing between one contact of the first series and the two next adjacent contacts of the second series.

5. A distributor, comprising, a circular series of contacts, a rotor arm having at one end a terminal for cooperating one at a time with the contacts of said series, a casing enclosing said contacts and arm, said casing having an inlet for connection to a supercharger and a drain outlet and being otherwise closed, a valve for opening and closing said outlet, said valve being biased to open position and being movable to closed position by air pressure during super-charging.

6. A distributor, comprising, a circular series of contacts, a rotor arm having at one end a terminal for cooperation one at a time with the contacts of said series, a casing enclosing said contacts and arm and having a drain outlet, a tube fixed to said casing and having an axial passage communicating with said outlet at one end and having the opposite end closed, said tube having a plurality of holes therein extending radially from said axial passage to the periphery of the tube, a casing fixed to said tube and providing an annular chamber surrounding said tube and closed at both ends, said casing having a plurality of openings through its peripheral wall spaced rearwardly from said radial holes by an axial distance greater than the diameter of said openings, said casing having a plurality of openings through the outer end wall thereof spaced forwardly from said radial holes by an axial distance greater than the diameter of said openings, all said openings having their axes located in different radial planes than those in which the axes of said radial holes are located, the radial distance between the outer periphery of the tube and the inner periphery of said casing being at least as great as the diameter of said openings.

7. A shielded distributor, comprising, a metallic casing having a peripheral wall and an end wall connected at one end thereof to said peripheral wall, said casing affording within it a distributor chamber closed at one end, a ring of insulating material fixed in said casing and bearing a circular series of contacts, a shaft mounted in said end wall coaxially of said series and carrying a rotor arm, a metallic cover secured to the other end of the peripheral wall and closing the other end of said chamber except for a single

opening located coaxially of said shaft, a second ring of insulating material fixed to said cover and bearing a second series of contacts located coaxially of said shaft, said rotor arm having on its end a contact to connect the contacts of the first series one at a time to contacts of the second series, the second ring having a substantially cylindrical part extending through the opening in said cover, terminal sockets provided in said last-named part, one for each contact of the second series and electrically connected one to each thereof, a metallic conduit having an elbow fixed to said cover and closing the opening therein, and spark plug wires in said conduit and connected one to each of said sockets.

8. A shielded distributor, comprising, a metallic casing having a peripheral wall and an end wall connected at one end thereof to said peripheral wall, said casing affording within it a distributor chamber closed at one end, a ring of insulating material fixed in said casing and bearing a circular series of contacts, a shaft mounted in said end wall coaxially of said series and carrying a rotor arm, a metallic cover secured to the other end of the peripheral wall and closing the other end of said chamber except for a single opening located coaxially of said shaft, a second ring of insulating material fixed to said cover and bearing a second series of contacts located coaxially of said shaft, said rotor arm having on its end a contact to connect the contacts of the first series one at a time to contacts of the second series, the second ring having a substantially cylindrical part extending through the opening in said cover, terminal sockets mounted in said last-named part one for each contact of the second series and electrically connected one to each thereof, a metallic conduit having an elbow fixed to said cover and closing the opening therein, spark plug wires in said conduit and connected one to each of said sockets, a seal ring of flexible material and a gland plate each perforated to receive said wires and clamped between said elbow and said part of the second ring, whereby the seal ring is compressed and bulged against said several wires and against the inner wall of the opening in the cover to seal off communication between said conduit and the distributor chamber.
